CLAIM

The ornamental design for a golf accessories holder, as shown and described.

DESCRIPTION

FIG. 1 is a front perspective view of a golf accessories holder showing my new design;

FIG. 2 is a front elevational view thereof;

FIG. 3 is a top plan view thereof;

FIG. 4 is a bottom plan view thereof;

FIG. 5 is a rear elevational view thereof; and,

FIG. 6 is a right side elevational view thereof, of which the left side elevational view is a mirror image.

The broken line showing of the golf ball is for illustrative purposes only and forms no part of the claimed design.
